DEVICE FOR APPLYING PELLETS TO AN UPRIGHT ADHESIVE SURFACE

Rufus W. Wilson, Huntingdon, Pa., assignor to Prismo Products, Inc., Dayton, Ohio, a corporation of New York

Application September 26, 1946, Serial No. 699,506

7 Claims. (Cl. 275—14)

1

This invention relates to a device for dispensing small pellets, and is designed primarily for applying minute glass spheres to vertical surfaces.

It is common practice for municipalities to paint or otherwise mark sections of street curbs to designate parking restrictions or the like. Reflectorized traffic stripes and other markings are being extensively used on streets and highways to provide improved night visibility, and for a like reason it is desirable that curb markings be reflectorized. Reflectorized markings on horizontal or substantially horizontal surfaces are provided by applying to the surface to be marked a layer of a light colored paint-like binder, of the desired dimensions, and distributing over said binder, before it has dried, a multiplicity of minute reflex-reflecting elements, usually glass spheres, which sink into and are partially imbedded in the binder. The spheres thus project above the binder and reflect light from the headlights of an automobile back to the driver of that automobile. It is impractical to reflectorize an upright surface of a curb or the like by such a method because of the difficulty of applying the spheres to the wet binder on said surface without excessive wastage of the spheres, and of securing proper distribution of the spheres on the surface.

One object of the invention is to provide a device by which such spheres may be easily and economically applied to the upright surface of a curb.

A further object of the invention is to provide a dispensing device which can be easily manipulated to distribute small pellets on a vertical or sharply inclined surface with substantial uniformity and without material waste.

A further object of the invention is to provide such a dispensing device which can be easily manipulated by one hand of the operator.

A further object of the invention is to provide such a dispenser which will apply the proper quantity of pellets to the surface being treated regardless of the speed at which the dispenser is moved along that surface.

A further object of the invention is to provide such a dispenser having parts which will engage and move over an adhesive surface without adhering thereto or materially displacing the adhesive.

Other objects of the invention may appear as the device is described in detail.

Fig. 1 is a perspective view of a dispensing device embodying the invention; Fig. 2 is a side ele-

2

vation of such a device; Fig. 3 is a top plan view of such a device; Fig. 4 is a vertical sectional view taken through the lower portion of such a dispensing device; Fig. 5 is a sectional detail view of one of the guide rollers; Fig. 6 is a front elevation, partly broken away, of a modified form of dispenser; and Fig. 7 is a side elevation of the dispenser of Fig. 6, with one end wall of the receptacle broken away to show the interior elements.

In these drawings I have illustrated two embodiments of my invention and have shown the same as designed primarily for applying glass spheres to curbs or to other upright surfaces to which a binder or adhesive has been applied, but it is to be understood that the dispenser as a whole, as well as the several parts thereof, may take various forms and that the dispenser may be used for various purposes, without departing from the spirit of the invention.

In the embodiment illustrated in Figs. 1 to 4 the dispenser comprises an upright receptacle 10 adapted to contain a quantity of minute glass spheres or other pellets, the term "pellets" being herein used to include small objects, or granulated materials, regardless of the shape thereof. The receptacle is shown as of rectangular construction and includes a front wall 11, a rear wall 12, end walls 13 and a bottom wall 14. The bottom wall 14 is provided with an elongate outlet 15 which may be of any suitable dimensions and is here shown as a longitudinal series of small circular openings 16 spaced one from the other and extending for substantially the full length of the bottom wall. A suitable distributing device is arranged to receive the pellets from the outlet 15 and to discharge the same against and distribute the same over an upright wall, to which a binder has been applied or which has been otherwise provided with an adhesive surface. In the construction shown this distributing device is in the nature of a chute 17 which preferably comprises a flat plate of a width approximating the width of the receptacle and which is rigidly secured to the receptacle, as by upright end portions 18 overlapping the lower portions of the end walls 13 and secured thereto, as by welding. The rear portion 19 of the chute is substantially parallel with the rear portion of the bottom wall and is spaced a short distance therefrom for a purpose which will hereinafter appear. The main portion of the chute extends beneath the outlet 15 and is inclined downwardly and forwardly with its outer or discharge end

spaced some distance beyond the plane of the front wall of the receptacle.

Suitable means are provided for controlling the flow of the pellets through the outlet 15, and in this form of the device a closure or gate 20 is supported beneath the bottom of the receptacle for movement into and out of a position to close the outlet. Preferably the closure is in the nature of a flat plate slidably mounted in the space between the rear portion 19 of the chute and the bottom wall of the receptacle and is movable forwardly and rearwardly to close and open the outlet. An inclined lip 21 is carried by the bottom wall in front of the outlet and arranged to be engaged by the forward end of the closure to force the latter into tight engagement with the bottom wall when it is moved to its closed position.

The dispenser is provided with suitable means whereby it may be supported and manipulated, and this means is here shown as a handle 22 rigidly secured to the back wall 12 of the receptacle. Any suitable operating means may be provided for actuating the closure but preferably this means is of such a character that it can be actuated by the hand which grasps the handle 22. In the particular arrangement illustrated this actuating means comprises a U-shaped lever 23 the arms of which are pivotally mounted between their ends on the respective end walls of the receptacle. The lower portions 24 of the arms are connected with the closure 20, as by pivotally mounting the same on trunnions 25 secured to and extending outwardly beyond the respective edges of the closeup. The upper portions 26 of the arms extend upwardly and rearwardly so that the transverse member or cross bar 27 of the lever extends across and is located adjacent to the upper portion of the handle where it may be easily engaged and actuated by the thumb of the hand which grasps the handle, the arrangement being such that a forward thrust on the cross bar will move the closure to outlet opening position. The closure is yieldably urged toward and retained in outlet closing position. In the arrangement shown there is mounted on one, or both, of the end walls 13 a spring 28 which acts on the lower portion of the adjacent lever arm to move the closure to outlet closing position when the pressure on the cross bar is relieved. The lever may conveniently be, and is here shown as, formed of stiff wire bent to the desired shape, each arm being provided with a coiled portion 29 which is mounted on a stud 30 projecting from the adjacent end wall of the receptacle.

When the pellets are to be applied to an upright surface to which a binder has been applied, or which has otherwise been rendered adhesive, the operator grasps the handle 22, positions the forward edge of the chute 17 close to but out of contact with the adhesive surface and then moves the device as a whole upwardly so that the discharge end of the chute moves upwardly in close relation to the adhesive surface. As this upward movement begins the lever is actuated to open the outlet so that the pellets will flow through the outlet onto the inclined chute, will be distributed over the upper surface thereof and will be discharged from the lower end of the chute with sufficient momentum to cause them to impinge against the adhesive surface. Thus upon each upward movement of the dispenser pellets will be distributed substantially uniformly over a portion of the surface having a width approximately equal to the width of the chute. The speed at which the dispenser is moved is regulated with

relation to the flow of pellets through the outlet 15 to avoid the discharge of more pellets than will adhere to the surface and to determine the extent to which the pellets will cover the surface. There may, of course, be some excess of pellets discharged from the chute, but in normal operation this excess will be small and the wastage of pellets will be negligible.

It is desirable that means be provided for properly positioning the discharge end of the chute with relation to the adhesive surface and for maintaining it in that position during the vertical movement of the dispenser. For this purpose the lower or discharge end of the chute may be provided with guides having narrow edges to contact the vertical surface and move over the same without adhering thereto and without materially displacing the adhesive. Preferably these guides are in the nature of rollers mounted adjacent the edges of the chute, and in the arrangement shown each roller comprises a ball bearing, the inner race 31 of which is mounted on a rod 32 secured to and extending laterally beyond the lower portion of the chute. The outer race 33 has secured thereto an annular member, such as a rubber tire 34, which is V-shaped in cross section so as to provide the same with a sharp circumferential edge which will engage the adhesive surface and move over the same without leaving any appreciable mark thereon.

In applying the pellets to the surface the dispenser may, of course, be moved either upwardly or downwardly, but a much more satisfactory application of the pellets is had when the receptacle is moved upwardly during the dispensing operation.

In Figs. 6 and 7 there is shown a dispenser having means for controlling the flow of pellets through the outlet in accordance with the distance which the dispenser moves with relation to the surface being treated, thus providing a uniform distribution of pellets on the surface regardless of the speed at which the dispenser moves. The receptacle 35 is similar to the receptacle 10 and is provided in its bottom wall 36 with an elongate outlet 37 which in this instance is preferably a continuous slot. Arranged within the receptacle and secured respectively to the front and rear walls thereof are inclined members 38 which extend for the full length of the receptacle and converge downwardly toward the outlet 37. Sealing elements 39 are supported on the bottom wall 36 on the respective sides of the outlet and extend between the lower edges of the converging members 38 and the bottom wall. Mounted within the receptacle between the spaced lower ends of the members 38 is a metering device which is here shown as a fluted rotor 40. The lower portion of the rotor extends slightly beyond the lower edges of the members 38 and has sealing contact with the adjacent ends of the sealing members 39. When the rotor is stationary it completely closes the outlet 37 and when it is rotated the flutes therein are filled with pellets and moved successively into line with the outlet, where the pellets are discharged through the outlet. The sealing members 39 are adjustable, as by means of screws 41 to maintain the same in sealing contact with the rotor. A chute 42 similar to the chute 17 is secured to the lower portion of the receptacle and provided at its lower or discharge edge with rollers 43 having sharp circumferential edges as above described. A driving connection is established between at least one of the rollers 43 and the rotor so that the

rotary movement imparted to that roller as it moves over the surface being treated is transmitted to the rotor and the latter is rotated at a speed conforming to the speed of rotation of the roller. Thus the quantity of pellets discharged from the receptacle is determined by the speed at which the receptacle is moved during the dispensing operation. The driving connection between the roller and the rotor may be of any suitable character, and as here shown a sprocket wheel 44 is secured to the roller 43 and is connected by a chain 45 with a sprocket wheel 46 mounted on the rotor shaft 47, which projects beyond the end of the receptacle.

While I have shown and described certain embodiments of my invention I wish it to be understood that I do not desire to be limited to the details thereof as various modifications may occur to a person skilled in the art.

Having now fully described my invention, what I claim as new and desire to secure by Letters Patent, is:

1. A device for applying pellets to an upright adhesive surface, comprising a receptacle adapted to contain a quantity of pellets and having an outlet for said pellets, a downwardly and forwardly inclined substantially flat chute of substantial width supported by said receptacle to receive pellets from said outlet and to discharge said pellets substantially uniformly over the full width of the forward edge thereof, guide means supported by the outer sides of said chute and extending forwardly beyond said forward edge of said chute to engage said upright surface and space said edge a predetermined distance therefrom, a handle secured to said receptacle and adapted to be gripped by the hand of an operator to support said receptacle and move the same vertically with said guide means in engagement with said upright surface, and means for controlling the flow of pellets through said outlet.

2. A device for applying pellets to an upright adhesive surface, comprising a receptacle adapted to contain a quantity of pellets and having an outlet for said pellets, a downwardly and forwardly inclined and substantially flat chute of substantial width supported by said receptacle in a position to receive pellets from said outlet, guide members supported by the sides of said chute adjacent the outer end thereof, extending forwardly beyond the forward edge of said chute, and having narrow edges to engage said upright surface and space said forward edge of said chute a predetermined distance therefrom, a handle adapted to be gripped by the hand of an operator to support said receptacle and move the same vertically with said guide members in engagement with said upright surface, and means for controlling the flow of pellets through said outlet.

3. A device for applying pellets to an upright adhesive surface, comprising a receptacle adapted to contain a quantity of pellets and having an outlet for said pellets, a downwardly and forwardly inclined and substantially flat chute of substantial width supported by said receptacle in a position to receive pellets from said outlet, guide members carried by said chute adjacent the respective sides thereof extending forwardly beyond the forward edge of said chute to engage said upright surface and space said forward edge of said chute a predetermined distance therefrom, a handle secured to said receptacle and adapted to be gripped by the hand of an operator to support said receptacle and move the same vertically with

5 with said guide members in engagement with said upright surface, and a device supported by said receptacle to control the flow of pellets through said outlet and having a part supported adjacent said handle for operation by the hand that grips said handle.

4. A device for applying pellets to an upright adhesive surface, comprising a receptacle adapted to contain a quantity of pellets and having an outlet for said pellets, a downwardly and forwardly inclined and substantially flat chute of substantial width supported by said receptacle in a position to receive pellets from said outlet, rollers mounted on said chute adjacent the respective sides thereof, projecting forwardly beyond the forward edge of said chute and having narrow edges to engage said upright surface and space said forward edge of said chute a predetermined distance therefrom, a handle secured to said receptacle and adapted to be gripped by the hand of an operator to support said receptacle and to move the same vertically with said rollers in engagement with said upright surface, and means for controlling the flow of pellets through said outlet.

5. A device for applying pellets to an upright adhesive surface, comprising a receptacle adapted to contain a quantity of pellets and having an outlet for said pellets, a downwardly and forwardly inclined and substantially flat chute of substantial width supported by said receptacle in a position to receive pellets from said outlet, rollers supported by said chute adjacent the respective sides thereof, extending forwardly beyond the forward edge of said chute and having narrow edges to engage said upright surface and space said forward edge of said chute a predetermined distance therefrom, a handle secured to said receptacle, extending rearwardly beyond the same and adapted to be gripped by the hand of an operator to support said receptacle and move the same vertically with said rollers in engagement with said upright surface to space said chute a predetermined distance therefrom, a gate to control the flow of pellets through said outlet, means biasing said gate to its closed position, and means supported adjacent said handle and operable by the hand that grips said handle for moving said gate against the action of said biasing means to an open position.

6. A device for applying pellets to an upright adhesive surface, comprising a receptacle adapted to contain a quantity of pellets having an outlet for said pellets, a downwardly and forwardly inclined and substantially flat chute of substantial width supported by said receptacle in a position to receive pellets from said outlet, rollers mounted on said chute adjacent the respective sides thereof and projecting forwardly beyond the forward edge of said chute and having narrow edges to engage said upright surface and space said forward edge of said chute a predetermined distance therefrom, a handle secured to said receptacle and adapted to be gripped by the hand of an operator to support said receptacle and to move the same vertically with said rollers in engagement with said upright surface, a fluted roller in said receptacle to control the flow of pellets through said outlet, a sprocket chain connecting said fluted roller with the first mentioned rollers for rotation thereby.

7. A device for applying pellets to an upright adhesive surface, comprising a receptacle adapted to contain a quantity of pellets having an outlet for said pellets, a downwardly and forwardly

inclined and substantially flat chute of substantial width supported by said receptacle in a position to receive pellets from said outlet, rollers mounted on said chute adjacent the respective sides thereof and projecting forwardly beyond the forward edge of said chute and having narrow edges to engage said upright surface and space said forward edge of said chute a predetermined distance therefrom, a rotatable device mounted in said receptacle to move measured quantities of pellets successively to said outlet, transmission means driven by said rollers for actuating said rotatable device at a speed determined by the speed at which said receptacle is moved vertically, and a handle secured to said receptacle and adapted to be gripped by the hand of an operator to support said receptacle and move the same vertically with said rollers in engagement with said upright surface to space said chute a predetermined distance therefrom.
